UNITED STATES PATENT OFFICE.

FRANK S. MOORE, OF WOODHAVEN, NEW YORK.

DESIGN FOR A TOY HORN.

56,832.

Specification for Design.

Patented Dec. 28, 1920.

Application filed May 20, 1920. Serial No. 382,988. Term of patent 14 years.

To all whom it may concern:

Be it known that I, FRANK S. MOORE, a citizen of the United States, residing in Woodhaven, county of Queens, State of New York, have invented a new, original, and ornamental Design for a Toy Horn, of which the following is a specification, reference being had to the accompanying drawing, forming part thereof.

The figure is an elevation of a toy horn showing my new design.

The tone producer is disposed in the cap.

I claim.

The ornamental design for a toy horn as shown.

FRANK S. MOORE.
